DESIGN FOR A SPOON OR OTHER ARTICLE
OF FLATWARE

William F. Moran, Meriden, Conn., assignor to
The Ellmore Silver Co., Inc., Meriden, Conn.,
a corporation of Connecticut

Application June 27, 1946, Serial No. 131,089

Term of patent 14 years

(Cl. D54—12)

To all whom it may concern:

Be it known that I, William F. Moran, a citizen of the United States, residing in the city of Meriden, county of New Haven, and State of Connecticut, have invented a new, original, and ornamental Design for a Spoon or Other Article of Flatware, of which the following is a specification, reference being had to the accompanying drawing, forming a part thereof.

Figure 1 is a front elevational view of a spoon showing my new design;

Figure 2 is an edge elevational view;

Figure 3 is a sectional view taken on the line 3—3 of Figure 1; and

Figure 4 is a sectional view taken on the line 4—4 of Figure 1.

The essential features of my design reside in the portions shown in full lines.

I claim:

The ornamental design for a spoon or other article of flatware, as shown and described.

WILLIAM F. MORAN.
